UNITED STATES PATENT OFFICE.

EPHRAIM H. MARSH, OF CEDAR VALE, KANSAS.

SUBMARINE GUN AND PORT THEREFOR.

SPECIFICATION forming part of Letters Patent No. 367,153, dated July 26, 1887.

Application filed July 29, 1886. Serial No. 209,493. (Model.)

To all whom it may concern:

Be it known that I, EPHRAIM H. MARSH, a citizen of the United States, residing at Cedar Vale, in the county of Chautauqua and State 5 of Kansas, have invented a new and useful Naval and Siege Gun and Submarine Ports, of which the following is a specification.

My invention relates to certain new and useful improvements in submarine guns and ports 10 for vessels, which are adapted to be employed in connection therewith, the object of my invention being to provide a submarine gun with means whereby a vacuum can be formed in the barrel in front of the charge, so as to do 15 away as far as possible with atmospheric pressure upon the projectile until it emerges from the gun, and by the special construction of the port, enabling the gun to be discharged below the water-line of a vessel without admitting water to the interior thereof.

With the above ends in view, my invention consists in the construction and combination 20 of the port and gun, as will be hereinafter fully set forth, and specifically pointed out in 25 the claims.

In the accompanying drawings, which illustrate my invention, Figure 1 is a side view of the barrel of a submarine gun constructed in accordance with my invention. Fig. 2 is a 30 sectional view taken through the port and longitudinally through the gun, said gun being in position for firing; and Fig. 3 is a side view of the interior of the port.

A refers to the gun or cannon, which is 35 mounted on a truck of proper construction, the breach and bore being of the usual form. The muzzle of the gun is turned on its exterior, as shown at H', so as to be cylindrical in cross-section, and the interior of the portion 40 H' is bored out, so as to be of greater diameter than the muzzle of the gun, as shown at F. Adjacent to this cylindrical portion of the muzzle a collar, h, is shrunk or otherwise attached to the gun, and at the front straight 45 edge of this collar is located a packing or washer, H, which is preferably made of rubber or other elastic material. The barrel A, near the muzzle, is provided with a tube, b, which is provided with a stop-cock, B. This 50 tube is connected to an air-pump by a flexible pipe, C, and between these may be located a

vacuum-gage, so as to indicate the rarity of the air in the barrel.

f refers to a convex disk, of glass or other suitable material, which is placed within the 55 enlarged portion F of the muzzle, a packing-ring, f', being placed between said disk and the flange at the muzzle of the gun.

When it is desired to prepare the gun for action, the gun is first loaded and the disk f, 60 with the packing-ring f', placed within the portion F, so as to rest upon the flange at the end of the bore proper. The stop-cock B is then turned and the air is pumped out of the bore, so as to produce as near a perfect vacuum 65 as possible in front of the charge. The stop-cock is then turned, when the gun, after being properly placed in the port, is ready to be fired.

a refers to the outer sheeting of the vessel, 70 immediately behind which is rigidly secured a re-enforcing-plate, a', the opening in the sheeting and plate a' being preferably the section of a cone, said opening being referred to by the letter g.

D represents a stationary board, which is 75 provided at its rear side with strips d, so as to provide a space between the same and the portion a', within which a sliding port, c, is adapted to move vertically, said sliding port 80 having an opening in its lower portion of about the same diameter as the portion H' of the gun. To the board D is rigidly attached a collar, c', the interior of which is of the same diameter 85 as the opening in said board. The collar and the portions hereinbefore referred to forming the port are rigidly bolted to each other, so as to permit the sliding gate or port c to have a vertical movement. The inner portion of the collar c' has pivoted thereto a swinging gate, 90 I, which is adapted to be folded so as to cover the opening in the port.

When it is desired to insert the gun A in the port, the swing-gate I is first loosened and elevated, and the gun is run into said port 95 until the extreme end of the muzzle abuts against the sliding port or gate c, when it is elevated, so as to permit the muzzle to pass through the opening therein. It will be noticed that the muzzle of the gun will support 100 this gate in an elevated position, so that when it is partially withdrawn from the port it will

fall automatically and prevent water entering the interior of the vessel. When the gun is discharged, the projectile will carry away the disk *f*, and, as there is no hydraulic or atmospheric pressure in the gun, the danger of the same bursting is obviated.

By means of the devices hereinbefore described, by the introduction of the vacuum in front of the charge the atmospheric resistance to the projectile is avoided and a greater force is obtained from the charge, and guns of ordinary construction, with my attachments applied thereto, may be fired below the water-line without injury, and the port is so constructed that it will be automatically closed after the gun is fired, as the sliding gate is supported upon the muzzle, which is withdrawn by the recoil.

I claim—

1. The combination, with a gun, of a gun-port, a sliding gate arranged between the inner and outer ends of said gun-port, and a pivoted gate arranged to close the inner end of said port, substantially as described.

2. The combination, with a submarine gun constructed substantially as described, and provided with a cylindrical portion at the muzzle thereof, and a flange for limiting its outward movement through the port, of a sliding gate, *c*, and collar *c'*, against which the packing adjacent to the flange will abut, substantially as shown, and for the purpose set forth.

EPHRAIM H. MARSH.
